UNITED STATES PATENT OFFICE.

WILLIAM J. GATES, OF LOS ANGELES, CALIFORNIA, ASSIGNOR TO AMERICAN AUTO LAUNDRY EQUIPMENT COMPANY, OF LOS ANGELES, CALIFORNIA, A CORPORATION OF CALIFORNIA.

ATOMIZING DEVICE.

Application filed December 9, 1924. Serial No. 754,875.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, 10 other than those specifically mentioned, are included within its scope.

My invention relates to atomizing valves and among its more salient objects are; first, to provide means for saturating a pressure air stream with water vapor, or other vapors, at ordinary temperatures; second, to supply a convenient means for proportioning the flow of air and liquid to the device to enable it to work satisfactorily under relatively 20 wide variations of air and liquid pressures, and under relatively wide differences between the respective pressures; third, to furnish facilities for controlling the discharge of the vapor saturated air, independent of 25 the proportioning adjustment; and, fourth, to accomplish the above in a device of great simplicity and relatively small cost.

Among other uses it will be found that my invention is particularly adapted for quickly 30 washing automobiles and the like where there are accumulations of hard dried mud, and where for one reason or another it is desired to use a minimum of water. In such use it has been found that a water saturated 35 air current at a relatively high velocity not only soaks and softens the mud with great rapidity, but causes its dislodgment much more quickly than it can be done by the use of a water jet operating at a permissible velocity. There are many secondary advantages in the use of air in this way, such as 40 freedom from splashing, economy of water consumption, and greater neatness of accomplishment.

Similarly, in the process of oil-spraying 45 railway trucks my device accomplishes the work with great rapidity and thoroughness, and by the use of an exceedingly small quantity of oil compared with older methods.

My several objects in the invention are attained in the manner illustrated in the accompanying drawing, in which the figure is 50 a longitudinal central section of the complete device, with certain of the working parts shown in elevation for greater clearness.

The atomizing portion of the device comprises a specially shaped body 5, tapped at 6 for connection to a source of compressed air, and at 7 for connection to a water system, or other liquid supply. An interior partition 8 60 separates the incoming fluids, and these are confined in chambers 9 and 10 except as permitted to escape therefrom through needle valves 11 and 12 respectively. In other words the rate of flow of air from chamber 9 65 through orifice 13 may be regulated by needle valve 11. Similarly the flow of water, or other liquid, from chamber 10 through orifice 14, may be regulated by needle valve 12.

A preferred form for needle valves for this 70 purpose is one having an end-slotted shank 15 adapted for screw driver adjustment. These valves are mounted in special bushings 16 which are provided with stuffing boxes and gland nuts 17, and the shanks are enclosed within screw caps 18. It has been found in the use of my device that, when the 75 adjustment of the needle valves is once properly made to suit the conditions of pressure and use, there seldom is any necessity for changing them. This form of construction reduces the tendency of operators to tamper with the adjustment, without making the valves inaccessible in case of necessity. It is possible, of course, to lock the valves in 80 adjusted position by various means that will readily occur to those having occasion to do this.

Above the atomizing device, and connected thereto by nipple 19, is a discharge regulating valve casing 20 having a relatively 90 large interior chamber 21. The form illustrated is a plug cock, controlled by handle 22, the flow being through the slot 23 in plug 24, as indicated by arrow 25. The outlet 26 of this valve is connected in any convenient manner to a hose, and operator's nozzle, for direct use on the work.

The upper portion of body 5 is interiorly 100 divided as shown in the figure, there being a relatively large outer flow passage 27 for air, and a smaller central flow passage 28 for liquid. The latter terminates in a small atomizing nozzle 29, extending well within and concentric with nipple 19. This construction affords, in cooperation with the 105 chamber 21, a simple and very effective modification of the Venturi tube principle, capable of thoroughly atomizing the liquid emerging from nozzle 29.

In operation the air, after passing orifice 13, flows upward as indicated by arrow 30 and acquires a high velocity in passing through the annular passage 31 constituting a cylindrical throat. The liquid jet issuing from nozzle 29 encounters this high velocity air current, is atomized by it, and caused to thoroughly impregnate the air stream. After passing through nipple 19, this moisture laden air is then suddenly expanded in chamber 21, and this results in partially vaporizing the already atomized liquid particles in the air current. The stream then passes through slot 23 in plug 24 to the operator's hose and nozzle in the form of a pressure stream of air thoroughly saturated with vapor. This stream is almost invisible when needle valves 11 and 12 are properly adjusted, on account of the fine atomization and partial vaporization of the liquid, but nevertheless will instantly saturate anything against which it is directed. The flow of the stream is regulated by handle 22 as already stated.

It will be obvious that my device may be used in any position such as horizontal, vertical or inverted. It will also be apparent that a plurality of these devices may be connected to a pair of air and liquid headers, and spaced for convenient use in garages, car washing tracks, and similar locations, where rapid washing, spraying, and similar work, is to be done with a minimum consumption of air and liquid.

The invention is well adapted for a large variety of uses not specifically mentioned herein, and all such uses are included within its scope.

I claim as my invention:

1. A device of the character described,

adapted for impregnating a stream of compressed air with water vapor, comprising; a pressure flow passage for air having a cylindrical constriction of substantial length and substantial reduction of cross-sectional area 45 therein; a pressure flow passage for water terminating in a nozzle having its outlet intermediately placed in the axis of said constriction; a chamber immediately beyond said constriction into which the constriction 50 abruptly expands; a valve immediately beyond said chamber for regulating the flow therefrom; and independently adjustable needle valves in said flow passages whereby the respective flows may be accurately regulated and apportioned.

2. A device of the character described, adapted for impregnating a stream of compressed air with water vapor, comprising; adjacent pressure chambers for air and 60 water; a pressure flow passage communicating with said air chamber through a needle valve and having a cylindrical constriction of substantial length and substantial reduction of cross-sectional area 65 therein; a pressure flow passage communicating with said water chamber through a second needle valve and terminating in a nozzle having its outlet intermediately placed in the axis of said constriction; an expansion chamber 70 immediately beyond said constriction into which the constriction abruptly expands; and a valve immediately beyond said expansion chamber for regulating the flow therefrom; said needle valves being independently adjustable exteriorly of the device for accurately regulating and apportioning the flows in said flow passages. 75

WILLIAM J. GATES.
